BOOKMARKER

Jack E. Jones and Joe D. Jones, High Point, N. C.

Application June 1, 1955, Serial No. 512,539

6 Claims. (Cl. 116—119)

This invention relates to bookmakers and more particularly to compact bookmarker provided with individual retractable indexing indicia that may be positioned in a predetermined sequential order to facilitate referencing. A related bookmarker is illustrated in our U. S. Patent No. 2,645,197, issued on July 14, 1953.

Previously the bookmakers employed by preachers, lecturers, research scholars, lawyers, and others using a standard reference work having employed flexible cords or other fixed length dividing elements which have on many occasions become entangled, twisted, and in general, unwieldy in use. Furthermore, it is not impossible with the bookmarker described in the above patent or other bookmakers to provide for a sufficient number of reference markers without making the apparatus cumbersome and awkward to use.

Therefore, it is an object of the present invention to provide a bookmarker having a plurality of individual resilient flexible book page separating cords that are individually retractable into one end of the bookmarker when the cords are not in use.

Another object of the present invention is the provision of a bookmarker that may be readily attached to a book spine, either of the open or tight back binding type, and is also provided with a set of individual elastic flexible book page separating elements, each of which may be extended to engage within a keeper in order to indicate a place within the book in a predetermined order and upon release from the keeper the individual cord is retracted into the bookmarker.

Still another object of the present invention is to provide a bookmarker with a plurality of individually engageable page separating elements that are extended when in use so as to be received within a suitable keeper in a desired sequential order and upon release of an individual element it will be retracted automatically into the bookmarker.

Yet another object of the present invention is the provision of a bookmarker that is readily attachable to a book and in which there is a plurality of individual flexible and resilient page separating elements that are individually accommodated in a suitable recess and may be arranged in rows within the recess.

Further objects of this invention are to provide a bookmarker that is readily attachable to and detachable from a book, one that is easy and simple to operate and requires a minimum of maintenance.

Other and further objects and many of the attendant advantages of this invention will become readily apparent as the invention becomes better understood from the following detailed description taken in connection with the accompanying drawings in which like characters of reference designate corresponding parts throughout the several views and wherein:

Fig. 1 is a perspective view of the present invention per se illustrating the bookmarker with a plurality of individual retractable page separating elements in the retracted position;

2

Fig. 2 is a reduced vertical sectional view taken substantially along the plane of line 2—2 of Fig. 1 and illustrates the invention attached to a book spine with several individual page separating elements in two indexing tiers;

5 Fig. 3 is a perspective view of the bookmarker of the present invention, somewhat reduced in size, as mounted to the spine of a book illustrating the instrument with a plurality of the page separating elements in extended position in an open book;

10 Fig. 4 is a perspective view of a bookmarker mounted to the spine of a book having an opened back book binding with the book in the closed position;

Fig. 5 is a transverse sectional view taken substantially along the plane of line 5—5 of Fig. 1.

15 Referring to the drawings in more detail and specifically to Figs. 1 and 2 there is illustrated therein a bookmarker 10 of the present invention which comprises a telescopically extendible book page separating cord receiver 11 that may be attached readily by a suitable fastening means

20 12 to a book adjacent to the book spine, and at one end of the bookmarker there is provided a plurality of elastic flexible book page separating elements or cords 13 that are individually extendible between the pages of a book to engage within a selected notch within the group of notches 14 that are cut in the plate 15.

The cord receiver housing 11 is preferably formed from a suitable rigid material that has a hollow longitudinal axis to form a protective casing that surrounds the cords 13. Although in the embodiment illustrated the receiver

30 11 is adjustable lengthwise so that the bookmarker may be accommodated to several book sizes, an integral receiver may be used as effectively for standard length volumes. Top and bottom fastening lugs 16 and 17 project outwardly a suitable distance from the receiver to retain and guide the fastening rod 18 and rod receiver 19,

35 respectively, which parts may be separated in order to mount the bookmarker to the spine 20 of a book 21, as illustrated clearly in Figs. 2 to 4. It will be readily apparent that other fastening means may be suitable for 40 mounting the bookmarker to either the spine of a book or to another position adjacent to the book spine.

Fastened, as by the screw 22 to the lower end of the receiver housing is the plate 15 which is provided with a straight portion 23, a first plane surface 24 and a second

45 plane surface 25. The surfaces 24 and 25 are designed to extend inwardly toward the book and these planes may be referred to hereinafter as indicia planes; the purpose for these planes will be described hereinafter. The series of laterally spaced opened notches 14 are cut into 50 the plate and preferably reach through the indicia planes 24 and 25.

Also fastened to the screw 22 is a cord clamping means 26 to which is fastened one end 27 of each of the plurality of flexible and resilient or elastic page separating

55 cords 13. The length of each elastic cord, in the relaxed condition, is approximately the length of the receiver in the closed or non-extended position. The free end of each cord is provided with a notch engaging key 28 that is securely fastened to the cord end so that when the individual cords are extended to pass between the book pages 29 to mark a position within the book the key 28 may be inserted into the desired plate notch for retention therein.

60 It has been found suitable to employ short tubular sleeves for the notch engaging keys 28 so that a cord end may be inserted into the sleeve and then the sleeve is compressed at one end 30 to retain the cord therein. This sleeve then serves as the notch engaging key for inserting or removing each cord from engagement with

65 70 the appropriate plate notch.

Spaced separators 31 may be mounted in the top of

the receiver in order to divide the cords into groups so that they will not become entangled and will provide for greater cord accessibility when the instrument is ready for use.

Although in the embodiment above described the page separating cords are made from elastic or other resilient material so that each cord may be individually retractable into the receiver housing, it is intended for illustrative purposes only and not for limitation since individual spring loaded roller elements, or the like, may be used in combination with a flexible cord connected to each roller element in order to retract the cord ends individually as they are disengaged from a plate notch.

The plate indicia planes 24 and 25 are set at suitable angles from the straight portion 23 providing rows or tiers which will accommodate a maximum number of cords positioned within the limitations of the width of a book. In this way the width of the plate is reduced appreciably thus making the bookmarker less conspicuous.

The bookmarker may be attached readily to the spine of a book having an open type binding 33 simply by slidably disengaging the rod 18 from within the rod receiver 19 and inserting the open end or top 32 of the receiver between the book spine and the open back binding of an open book. The rod receiver may be positioned approximately in the center of the open book then the receiver is telescopically extended to the correct position adjacent to the book spine. The rod 18 is inserted into the rod receiver 19 to be frictionally retained therein.

With the bookmarker mounted in position on the book an individual cord 13 may be extended from within the receiver housing and placed between the pages of a book in which a selected passage appears, preferably in a reverse order of reference, and the attached notch engaging key 28 may be inserted into a selected plate notch 14 in the desired sequence. The last passages to be referred to are positioned first and the keys to be referred to last are arranged to engage the notches in the first plane surface 24, the remaining keys are then positioned in order on the second plane surface 25. The portion of the cords adjacent the keys may be crossed or placed over one another with the uppermost cord being removable first from within a notch to indicate the first reference passage before the next succeeding uppermost cord is removed from its corresponding notch position.

When the bookmarker is to be attached to a tight back type book binding the receiver may be mounted flush to the binding and book spine and the fastening means is attached substantially as described above.

Obviously many modifications and variations may be made in the construction of the bookmarker, the cord receiver housing and the bookmarker fastening means as well as the elastic book page separating members without departing from the real spirit and purpose of this invention. It is therefore to be understood that within the scope of the appended claims many modified forms of structure as well as use of mechanical equivalents may be reasonably included and therefore modifications are contemplated.

What is claimed is:

1. A bookmarker comprising an elongated cord receiver housing having means thereon for attachment to a book spine, a plate mounted on one end of the receiver housing and having a plurality of spaced notches therein, flexible resilient page separating cords attached at one end to the other end of the receiver housing from the plate and having means at the free end of each cord to engage within a plate notch in the cord extended condition, said cords being retractable into the receiver housing in the relaxed condition when released from a plate notch.

2. A bookmarker comprising an elongated cord receiver housing having means thereon for attachment to

a book spine, a plate mounted on one end of the receiver housing and having a plurality of spaced notches therein, elastic page separating cords attached at one end to the other end of the receiver housing from the plate and having means at the free end to engage within a plate notch in the cord extended condition, said cords being retractable into the receiver housing in the relaxed condition.

3. A bookmarker comprising an adjustable telescoping cord receiver housing provided with means for attachment to a book spine, a plate having laterally spaced notches mounted at one end of the receiver housing, a plurality of flexible resilient book page separating cords secured at one end to the receiver housing and retractable therein, each of said cords being provided with a notch engaging key to be selectively positioned in an extended condition in a plate notch in sequential order and upon release from a notch a cord will be retracted into the receiver housing.

4. A bookmarker comprising an adjustable elongated cord receiver provided with means for mounting the receiver housing to a book and having upper and lower ends and an opening at the upper end, a plurality of elastic flexible book page separating cords fastened in the receiver housing and retractable through the opening in the receiver housing, each of said cords having a notch engaging key at the free end, a plate mounted at the lower end of the receiver housing provided with key receiving notches to receive the cord engaging keys individually in a predetermined order in the cord extended condition.

5. A bookmarker comprising a telescopically elongatable receiver housing having a substantially hollow longitudinal core and provided with means for mounting the receiver housing to a book spine, a plate mounted adjacent to one end of the receiver housing, said plate having a plurality of indicia planes therein to form individual rows and a group of laterally spaced key retaining notches therein, at least one of said notches extending continuously into said planes, a plurality of flexible and resilient book page separating elements secured at one end to the receiver housing and retractable therein, each of said cords being provided with a notch engaging key at the free end to be selectively positioned through the pages of a book in an extended condition to engage within a plate notch in sequential order at a plane position and whereby upon release of an element from a plate notch said cord is retractable into the receiver housing.

6. A bookmarker comprising an elongatable receiver housing having a substantially hollow longitudinal core and provided with means for mounting the receiver housing to a book spine, a plate mounted adjacent to one end of the receiver housing, said plate having a plurality of indicia planes therein to form individual rows and a group of laterally spaced key retaining notches therein, at least one of said notches extending continuously through substantially all the indicia planes, a plurality of elastic flexible book page separating elements retained at one end to the receiver housing, each of said cords being provided with a notch engaging key to be selectively positioned through the pages of a book in an extended condition to engage within a plate notch in sequential order at a desired plane position and whereby upon release of an element from a plate notch said cord is retractable automatically into the receiver housing.
